UNITED STATES PATENT OFFICE.

CHARLES C. BROWN, OF HORSE CAVE, KENTUCKY.

MAIL-BAG CATCHER.

1,297,079.

Specification of Letters Patent. Patented Mar. 11, 1919.

Application filed October 28, 1918. Serial No. 260,043.

To all whom it may concern:

Be it known that I, CHARLES C. BROWN, a citizen of the United States, residing at Horse Cave, in the county of Hart and State 5 of Kentucky, have invented new and useful Improvements in Mail-Bag Catchers, of which the following is a specification.

This invention is an improved mail bag catcher for use in the door of a mail car for 10 catching mail bags as the car passes stations, the object of the invention being to provide an improved device of this kind embodying a crane, means to hold the crane in position to catch and means operated by a mail sack 15 on the crane to hold the mail sack on the crane, and to release the crane holding means and thereby cause the crane to drop to initial position and avoid the necessity of manually operating the crane so that the mail clerk 20 can attend to his other duties.

With the above and other objects in view, the invention consists in the construction, combination and arrangement of devices hereinafter described and claimed.

25 In the accompanying drawings:

Figure 1 is an elevation of a portion of a mail car provided with a mail bag catcher constructed and arranged in accordance with my invention, and showing the crane in initial inoperative position.

Fig. 2 is a horizontal sectional view of the same on the plane indicated by the line 2—2 of Fig. 1 and showing the crane in set position ready to catch a mail bag.

35 Fig. 3 is a vertical sectional view of the same on the plane indicated by the line 3—3 of Fig. 1.

The mail bag catching crane 1 comprises a rock shaft 2 which extends across the 40 doorway 3 of a mail car and is mounted at its ends in bearings 4. The arm 5 of the crane extends at a suitable angle from the rock shaft and is connected thereto at one end as at 6.

45 On the outer side of the rock shaft is a spring detent 7 which is secured to the rock shaft at one end, as at 8, and which is arranged at an angle to the rock shaft and extends toward the crotch of the crane and 50 also outwardly toward the crane arm 5.

Said spring detent has an arm 10 which extends inwardly therefrom over the rock shaft and is provided at its inner end with a downwardly turned flange 11. A stud 12 projects from the inner side of the rock 55 shaft and is arranged below the flange 11.

A supporting arm 13 is pivoted as at 14 at one end to a bracket 15 which is secured in one side of the doorway, said arm being thus arranged for swinging movement and 60 being adapted to bear on the stop stud 12 of the rock shaft to hold the crane in horizontal position and with its arm 5 extending outwardly from the car to catch a mail bag.

As the car passes a station at which the 65 mail bag is suspended the ring of the mail bag is caught by the crane arm 5 and passes longitudinally on said arm to the crotch of the crane and as it does so the detent 7 is engaged behind the ring, thus preventing 70 the mail bag from dropping from the crane and at the same time the detent is moved inwardly, thus causing its arm 10 and flange 11 to push the stop arm 13 from the stop stud 12, thus entirely releasing the crane so 75 that the latter turns downwardly to its normal position and is caused to lie close to the side of the car. The mail bag can then be removed from the crane by the operator.

It will be understood that my improved 80 mail bag catcher requires no further attention on the part of the operator after it has once been set as the operation of catching the mail bag and of releasing and causing the crane to drop is entirely automatic.

85 While I have herein shown and described a preferred embodiment of my invention, I would have it understood that changes may be made in the form, proportion and construction of the several parts without departing from the spirit of my invention and within the scope of the appended claim.

Having thus described my invention, I claim:

A mail bag catcher of the class described, 95 comprising a rock shaft mounted in bearings, extending across the door of a mail car and provided with a crane arm extending outwardly and longitudinally therefrom, said rock shaft having an inwardly extend- 100

ing stop stud, a spring detent secured at one end to the rock shaft, extending therefrom toward the crane arm and provided with an inwardly extending arm, and a supporting arm pivotally mounted in one side of a doorway and arranged to bear on the stop stud of the rock shaft when the crane is in set

position, said detent and its arm serving to disengage said supporting arm from the stop stud when the detent is engaged by a mail bag caught on the crane arm. 10

In testimony whereof I affix my signature.

CHARLES C. BROWN.
